REFRIGERATION APPARATUS

Ludwig Roebel, Mannheim, Germany

Application November 1, 1930, Serial No. 492,693,
and in Germany December 5, 1929

7 Claims. (Cl. 62—115)

My invention relates to improvements in refrigeration apparatus.

In the attempt to build reciprocating piston compressors which form a constituent part of a refrigerator, in which compressors there is no necessity to render the piston or the crank shaft tight to the outside, different methods of construction have been developed which utilize the centrifugal force acting on the piston as 5 the driving force. It is well known that the centrifugal force is evolved by giving the compressor cylinders a rotation about two axes of which one is outside the cylinders and the other passes through the central position of the 10 pistons. Thus the individual cylinders, being subjected to a rotation about their own axes, the centrifugal force set up is caused to act on the pistons alternately in each direction.

One embodiment of my invention differs from 20 the various constructions already known in that the centrifugal force does not directly set the pistons in motion, but serves to give one of the parts of the machine, preferably the compressor piston or compressor cylinder, a position which 25 is constantly radial to the main axis, the relative motion of other parts to this position being used to drive an eccentric. The other machine parts to which this applies are the cylinders or pistons of the compressor.

30 My invention resides in the improved apparatus and method of operation of the character hereinafter described and claimed.

For the purpose of illustrating my invention, an embodiment thereof is shown in the 35 drawing, wherein

Figure 1 is an elevational view, partly in section, of refrigerating apparatus constructed and operated in accordance with my invention; and

40 Fig. 2 is a fragmentary, sectional view, illustrating a modification.

In Fig. 1, supporting structure 1 is built in the form of a disc and casing, and rotates about the shaft 2 at uniform speed. In the casing of 45 this supporting structure are connected one or more units (referred to hereinafter as refrigerators), which consist chiefly of the compressor housing 3, the piston 4, the cylinder 5, the tube 6, the atomizing jet 7 and the vaporizer 50 chamber 8, and which rotate independently about the shaft 2. Each refrigerator however rotates, as well, about its axis 9, this motion being imparted to it by means of a gear wheel 10 which engages with the stationary pinion 11.

55 In accordance with the present invention,

the compressor piston is driven by means of an eccentric 12 keyed to the pipe 13. The movement by this eccentric is caused by the compressor cylinder 5, which is loose on the pipe 13, being continuously compelled, by the centrifugal force due to its rotation about the shaft 2, to take up a position which is radial to the main shaft 2 as well as to the secondary axis of rotation 9, while the pipe 13, which is fixed to and is in effect integral with the housing 3 and the chamber 8, rotates about its own axis with the housing and chamber, and also revolves about the shaft 2.

Fig. 2 shows a reversal of the arrangement shown in Fig. 1, and illustrates the case in 70 which the compressor piston 4, instead of the cylinder 5, is loose on the pipe 13 and is held by centrifugal force in a position which is always radial to the main axis of rotation 2, the compressor cylinder being loose on and given 75 a reciprocating motion by the eccentric 12.

The refrigerant is in both cases drawn from the evaporating chamber through the outer pipe 13 and the passage 14 in the cylinder wall, and is then compressed and forced through the flap 80 valve 15 into the inside of the housing 3, from whence it reaches the evaporating chamber again by means of the opening 16, the tube 6 and the atomizing nozzle 7. The refrigerating effect, produced at the outer surface of the 85 evaporating chamber by the evaporation of the refrigerant, may be transferred in a known manner to the point where the cooling is to be done by means of any medium such as air or water.

90 The invention claimed is:

1. Refrigeration apparatus comprising structure sealed at all points over its outer surface against ingress of fluid to or egress of fluid from its interior, means for compressing a refrigerant, a portion of said structure containing and providing a compression chamber for said compressing means, another portion of said structure constituting an evaporating chamber, said structure provided with a passage for admitting the compressed refrigerant from the compression chamber to the evaporating chamber, said structure provided with a passage for permitting return of the refrigerant from the evaporating chamber back to said compressing means, means supporting said structure for rotation about a given axis and for revolution bodily about another axis, and characterized by the fact that said compressing means comprises cylinder and piston members held against rotation about said 100 105 110

given axis by centrifugal force developed incident to revolution of said structure bodily about said second-named axis.

2. Refrigeration apparatus comprising a self-contained refrigerating unit comprising a compressor section and an evaporating section, means supporting said unit for rotation about a given axis and for revolution bodily about another axis, cylinder and piston members forming part of said compressor section, and characterized by the fact that said members are held against rotation about said given axis by the centrifugal force developed incident to revolution of said unit about said second-named axis.

15 3. In refrigeration apparatus, structure supported for rotation about a given axis and comprising a compressor section and an evaporating section and a pipe connecting said sections and fixed for rotation therewith, refrigerant-compression means disposed within said compressor section and comprising a piston member and a cylinder member, said members supported by said pipe, an eccentric fixed on said pipe, one of said members being driven by said eccentric, and means supporting said structure for revolution bodily about an axis distinct from the axis of rotation.

4. In refrigeration apparatus, a plurality of independently operable refrigerating units, and 30 means common to said units and supporting the same for rotation about their respective longitudinal axes and for simultaneous revolution bodily about an axis disposed between said longitudinal axes, each of said units including piston and cylinder members held against rota-

tion about the longitudinal axis of the unit by centrifugal force developed incident to revolution of the unit bodily about the axis between said longitudinal axes.

5. In refrigeration apparatus, a refrigerating unit comprising a compressor chamber and an evaporating chamber and a pipe connecting said chambers, said unit supported for rotation about the axis of said pipe and for revolution bodily about another axis, an eccentric disposed within said compressor chamber and fixed for rotation with said chambers and pipe, and cylinder and piston members disposed within said compressor chamber, the piston member being driven by said eccentric. 80

6. In refrigeration apparatus, a refrigerating unit comprising a compressor chamber and an evaporating chamber and a pipe connecting said chambers, said unit supported for rotation about the axis of said pipe and for revolution bodily about another axis, an eccentric disposed within said compressor chamber and fixed for rotation with said chambers and pipe, and cylinder and piston members disposed within said compressor chamber, the cylinder member being driven by 95 said eccentric. 90

7. In refrigeration apparatus, structure supported for movement to develop a centrifugal force, a piston member and a cylinder member and an eccentric member effective jointly to 105 compress a refrigerant, said piston and cylinder members being arranged for control thereof by the centrifugal force developed. 100
